Patented July 13, 1976

240,486

RACK FOR GARDEN IMPLEMENTS AND HOSES

Dieter Raffler and Franco Clivio, Ulm, Germany, assignors to Kupex AG, Glarus, Switzerland

Filed Mar. 1, 1973, Ser. No. 336,898

Claims priority, application Germany Oct. 14, 1972

Term of patent 14 years

Int. Cl. D6—06, D8—08

U.S. Cl. D6—112

FIG. 1

FIG. 1 is a perspective view of a rack for garden implements and hoses showing our new design.

FIG. 2 is a front elevational view of the design.

FIG. 3 is a rear elevational view of the design.

The side of the rack not shown in the drawing is identical to that illustrated.

We claim:

The ornamental design for a rack for garden implements and hoses, as shown and described.
